UNITED STATES PATENT OFFICE

CHARLES JOHNSON, OF CLEVELAND, OHIO

VALVE

Application filed December 18, 1929. Serial No. 414,985.

This invention relates to valve means for a gas line, the general object of the invention being to provide means for closing the line and keeping it closed if the pressure therein should fall so that when the pressure returns, gas cannot reach the burners and other devices and thus escape and injure persons in a room or building.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a similar view but with the valves in closed position.

Figure 2 is a view showing how the valves are raised.

In these views, the numeral 1 indicates a V-shaped member which has an inlet nipple 2 at one side thereof and an outlet nipple 3 at the opposite side, these nipples being in alignment and communicating with a chamber 4 formed at the lower part of the V-shaped member. The upper portions of the limbs of the V-shaped member are closed by the blocks 5 preferably made from light material, such as aluminum. A disk shaped valve 6 is hingedly connected with the block in the discharge side of the member, as shown at 7, and a similar valve 8 is hingedly connected with the lower end of the other block, as shown at 9, these valves being so arranged that they will normally drop to positions closing the nipples under the action of gravity.

A rod 10 passes through the block 5 on the inlet side of the device and is normally held in raised position by a spring 11. The lower end of the rod is formed with a hook 12 so that by lowering the rod and placing the hook under the valve 6, the same can be raised, as shown in Figure 2, and when this valve is raised, the pressure of gas entering the device will raise the valve 8 and the two valves will

remain in position, due to the pressure of gas acting on the valve 8, to permit flow through the outlet nipple. If the pressure should fall for any reason, the valve 8 would drop. Then if the pressure should rise again, the valve 8 might be opened, and by hitting the rod 10, the valve 6 with initial pressure thereagainst will be released from the hook and closed so the gas could not escape from the device, due to the fact that the valve 6 is closed. It is then necessary to lower the rod 10 and place its hook in engagement with the valve 6 and then pull up the rod to raise the valve 6. When this is done, the valve 8 will swing up and with the valve 6 open they will remain open until the pressure again drops.

Thus I have provided simple means for preventing gas or the like from escaping from burners or the like after the pressure has dropped to a point where the flames at the burner will be extinguished. This invention eliminates danger of asphyxiating persons when the pressure rises again after the flames have been extinguished.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A device of the class described comprising a V-shaped member of hollow construction, an inlet nipple connected with one side thereof, an outlet nipple connected with the opposite side thereof, a pair of flap valves in the member and closing the inner ends of the nipples under the action of gravity, means for raising the outlet valve whereby the pressure of gas will raise the other valve as long as the pressure continues.

2. A device of the class described comprising a V-shaped member of hollow construction, an inlet nipple connected with one side thereof, an outlet nipple connected with the opposite side thereof, a pair of flap valves in the member and closing the inner ends of the nipples under the action of gravity, means for

raising the outlet valve whereby the pressure of gas will raise the other valve as long as the pressure continues, such raising means comprising a rod slidably arranged in one limb of the V-shaped member and having a hook at its lower end for raising the outlet valve and a spring for normally holding the rod in raised position.

19 In testimony whereof I affix my signature.
CHARLES JOHNSON.
